EAR INSERT FOR A HEARING AID

Abraham Feingold, 32—33 147th Place,
Flushing, N.Y. 11354

Filed Aug. 5, 1970, Ser. No. 24,309

Term of patent 14 years

Int. Cl. D14—04; D24—99

U.S. Cl. D26—14

FIG. 1

FIG. 2

FIG. 3

FIG. 4

FIG. 5

FIG. 1 is a front elevational view of an ear insert for a hearing aid showing my new design;

FIG. 2 is a right side elevational view thereof;

FIG. 3 is a rear elevational view thereof;

FIG. 4 is a top plan view thereof; and

FIG. 5 is a bottom plan view thereof.

I claim:

The ornamental design for an ear insert for a hearing aid, substantially as shown.
